United States Patent Office

Des. 229,402
Patented Nov. 27, 1973

229,402

TRAILER

Richard D. Edler, 1255 Valley Road,
Bannockburn, Ill.

Filed Sept. 29, 1971, Ser. No. 184,976

Term of patent 14 years

Int. Cl. D12—10

U.S. Cl. D14—3 E

FIG. 1

FIG. 2

FIG. 3

FIG. 4

FIG. 5

FIG. 1 is a side elevational view of the trailer showing my new design;

FIG. 2 is a top plan view thereof;

FIG. 3 is an elevational view of the side of the trailer opposite to that illustrated in FIG. 1;

FIG. 4 is an elevational view of one end of the trailer as seen in the direction of the arrows 4—4 of FIG. 3; and

FIG. 5 is an elevational view of the end of the trailer opposite to the end shown in FIG. 4.

The broken lines are for illustrative purposes only, and constitute no part of the claimed design.

I claim:

The ornamental design for a trailer, as shown and described.
